BOTTLE CLOSURE

Joseph H. Ramsey, Albany, N. Y.

Application December 27, 1933, Serial No. 704,156

13 Claims. (Cl. 215—84)

My invention relates to a new and improved method for securing protective skirted paper or tissue caps upon the mouth portions of bottles, containers and the like and more particularly upon the mouth portions of milk bottles which, because of the large quantities in daily use, provide a wide field of usefulness for my improvements.

Milk bottles are exceptionally proficient carriers of disease germs as they are commonly handled by their mouth portions in the collection of the empty ones and in the distribution of the re-filled ones. Also the mouth portions of milk bottles are usually exposed to contamination from the dirt and dust of the streets; both during delivery and while placed at doorways etc., and germs that find lodgement at the mouths of such bottles are in circumstances favorable to their multiplication and growth as milk affords an excellent medium for their propagation. When milk is poured out of a bottle it passes over considerable of the mouth portion that has been exposed to contamination and germs that have found lodgement upon it may readily be washed into the milk stream and become a menace to the health of the persons who consume it.

As the foregoing is matter of more or less common knowledge, it is customary among many milk distributors to protect the mouth portions of milk bottles with skirted or hooded caps, but because of their relatively high cost and the expense of securing them upon the necks of the bottles, such protection is generally restricted to the more expensive types of milk products such as the "grade A" and cream.

The usual form of protection consists of a pre-formed and printed cap of opaque paper in the form of an inverted cup which, after being placed over the mouth portion of the bottle, has its lower portion or skirt crimped tightly around the circumference of the bottle neck where it is secured by an annular, super-imposed ring of metal strip or wire. This means of securing the hooded cap has objections in that metal bands are relatively expensive in themselves and are also difficult for the consumers to remove with the result that the paper caps may be merely cut away with a knife over the bottle openings leaving the bands to be removed later at the bottling plants. When wires are used as a securing means they are, in some instances, of very fine gauge and it may be necessary to coat them with solder at an additional expense. Such wires with their small section and sharp ends may cut or puncture the skin of persons handling the bottles and so cause serious injuries and infections.

Attempts have been made in the past to overcome the objections to metallic fastenings by substituting either a twine or paper strip. The twine may be secured by sealing the ends with a metal clip, or with sealing wax which, when it sets, forms a hard nubbin about the ends of the twine to hold them together. Paper strip may be secured around and upon the skirt portion of the hood cap by coating its inner surface with a waterproof cement. Twine, secured at the ends with a metal clip is difficult to remove unless a knife is available for cutting the twine. Metal clips or pieces of wire may get into garbage cans with possible unfortunate results to the animals that are fed upon the garbage. Sealing wax used for securing the ends of the twine is brittle and fragile when cold and may become broken in the handling and transportation of the bottles. Paper strips have relatively little tensile strength compared with metal or twine and it is possible for such fastenings to become dislodged in the handling of the bottles. Any form of knot offers such technical difficulties in the design, construction and operation of automatic mechanical means for forming the tie as to be relatively impracticable compared with the simpler mechanisms available for metallic bands and wires. This is also true of fastenings having their ends tucked beneath circumferentially multiple windings.

In my method for securing skirted caps to the mouth portions of bottles I overcome the objections and disadvantages of these earlier types in a simple and effective manner and at a considerable saving in the cost of materials.

Referring to the drawing forming a part of this application I show the mouth portion of a bottle, 1, of the sort ordinarily employed in the dairy industry and having the usual printed cap, 2, seated within the mouth, 3, of the bottle. Over the exterior of the mouth portion I place a sheet of tissue or fabric, which may be a smooth-surfaced and/or transparent cellulosic tissue such as "cellophane" and which may be pre-formed, preferably from a disc, either directly upon the mouth portion of the bottle or in any other suitable manner, to comprise an inverted cup or skirted hood cap, 4, the lower edges of which extend downward and well over the pouring surface, 5, of the bottle for a distance sufficient to provide a bearing surface for the securing means. In order to crimp the skirt of the cap securely upon the outer circumference of the mouth portion of the bottle I place, mechanically or otherwise, upon

and around it a double loop, 6, of treated twine of adequate size and strength for the purpose and formed in the manner known and shown in the drawing as a clove hitch. When the extending ends, 7, of the twine are pulled uniformly apart the double loop will contract concentrically upon and around the skirt of the cap until the skirt portion is compressed snugly around the neck of the bottle after which the ends of the string are clipped off at a suitable length from their point of contact with the skirt. It will be noted that the clove hitch is peculiarly adapted for this purpose as it is of such simple form that it lends itself easily to mechanical application and, in the concentric contraction of its loops, it will not tend to tear or distort the skirt of the cap. The twine may be easily removed from its secured position by grasping either one of the extending ends, 7, with the fingers and pulling it backward upon itself which causes the overlapping loop wave, 8, to roll backward along the strand until it uncovers the other extending end, 7, after which the twine is free for removal. However, in order to adapt this simple form of securing means to the purpose, the clove hitch in itself is insufficient for the reason that it tends to unwind like a clock-spring as soon as the tightening pull on the ends, 7, is released and thus it is neither commonly intended nor useful for maintaining its constructed form when the ends are so released. It thus becomes necessary, particularly in combination with a glazed or smooth surfaced material such as "glassine" or "cellophane" offering little or no frictional resistance, to provide a treated twine which will cling to the skirt surface and thereby counteract the tendency to unwind in the course of ordinary handling of the bottle but which will not adhere sufficiently to preclude the tightening of the loops securely upon the skirt. Furthermore, the twine when treated should function properly within usual variations in temperature and it should maintain the aforementioned characteristics when wet.

In my method I prefer to treat the twine with suitable material before it is positioned upon the skirt of the cap but obviously it may be so treated after it has been positioned upon the skirt or the skirt may be coated before the twine has been positioned without departing from the scope of my invention.

Being unsuccessful in obtaining a commercially available twine having the aforesaid characteristics applicant experimented at length with various sorts of coatings to the end that material comprising a combination of resin and resin oil of a semi-fluid consistency was found to be satisfactory and is preferred for this purpose. Coatings of powdered resin, or canauba wax combined with beeswax, give reasonably satisfactory results and there are doubtless other types of gummy or clinging materials that may suffice for the purpose.

In one form of my improved method I prefer to form a circular sheet of "cellophane" directly upon the mouth portion of the bottle into a skirted hood cap, for "cellophane" is both inexpensive and transparent and the printed matter on the underneath cap, 2, which usually designates the product in the bottle may be conveniently read through it. Skirted hood caps of opaque paper such as are generally used must be printed at additional cost to obtain the same results. Because of the soft, flexible characteristics of my twine in combination with the concentric action of its

loops in tightening the skirt upon the bottle and the clinging action of its contracting surfaces, it is particularly adaptable to the smooth, glassy surface of "cellophane." Where fused seals are used the application of heat to "cellophane" may cause it to become brittle and easily broken in use. 5

The savings effected together with the other advantages of my invention make it commercially practicable for use upon milk products of the lower grades and so enhance public health and 10 well being.

The adaptation of the clove hitch with its treatment to prevent the loosening of the coils upon the skirt portion of a hood cap in ordinary handling is illustrative of one form of my invention which is, of course, applicable to any relative arrangement of loops and ends of twine upon the skirt portion of a hood cap wherein the addition of a gummy material serves to prevent such loosening. 15

I do not wish to limit the application of my invention to the particular product described herein as it is equally applicable to many other forms of containers and receptacles, nor to the exact method herein disclosed as it is obvious that variations may be made without departing from the invention. 20

Having thus described my invention, I claim:

1. In combination, a skirted hood cap adapted to be placed over the mouth portion of a bottle, 30 loops of twine in the form of a clove hitch positioned upon and around the skirt of the cap, and a gummy material applied to the twine at the clove hitch so as to secure the loops in assembled position on the skirt of the cap. 35

2. In combination, a skirted hood cap adapted to be placed over the mouth portion of a bottle, loops of twine positioned upon and around the skirt of the hood cap and upon the end portions of the twine, and a gummy material applied to 40 the twine to cause adjacent surfaces of the loops to cling to each other and to the skirt of the cap so as to secure the cap in assembled position upon the mouth portion of the bottle.

3. In combination, a skirted hood cap adapted to be placed over the mouth portion of a bottle, 45 loops of twine in the form of a clove hitch positioned upon and around the skirt of the cap, and a material applied to the twine for securing the end portions thereof together, said material being such as will cause the loops to cling to each other and to the surface of the skirt portion of the hood cap when in assembled position upon the mouth portion of the bottle and as will maintain the loops securely in assembled position. 50

4. In combination, a skirted hood cap adapted to be placed over the mouth portion of a receptacle, twine looped in the form of a clove hitch positioned upon and around the skirt of the cap, and gummy material applied to the twine, said 60 gummy material being such as to provide a limited tendency for the loops to cling to each other and to the skirt portion of the hood cap in such degree as will permit the loops and skirt to be drawn tightly into operative position when pull is applied to the ends of the twine and as will maintain the loops securely in assembled position.

5. In combination, a skirted hood cap adapted to be placed over the mouth portion of a receptacle, loops of twine positioned upon and around a skirt portion of smooth surfaced material and upon the end portions of the twine, and gummy material applied to the twine, said gummy material being such as to provide a limited tend- 70

ency for the loops to cling to each other and to the skirt portion of the hood cap in such degree as will permit the loops and skirt to be drawn tightly into operative position when pull is applied to the ends of the twine and as will maintain the loops securely in assembled position.

6. In combination, a skirted hood cap having a transparent top and adapted to be placed over the mouth portion of a receptacle, loops of twine positioned upon and around the skirt of the cap and upon the end portions of the twine, and a gummy material applied to the twine, said gummy material being such as to provide a limited 10 tendency for the loops to cling to each other and to the skirt portion of the hood cap in such degree as will permit the loops and skirt to be drawn tightly into operative position upon the mouth portion of the receptacle when pull is applied to the ends of the twine and as will maintain the loops securely in assembled position.

7. In combination, a skirted hood cap having a transparent top and adapted to be placed over the mouth portion of a receptacle, twine looped in the form of a clove hitch positioned upon and around a skirt portion of smooth surfaced material, and a gummy material applied to the twine, said gummy material being such as to provide a limited tendency for the loops to cling to each other and to the skirt portion of the hood cap in such degree as will permit the loops and skirt to be drawn tightly into operative position upon the mouth portion of the receptacle when pull is applied to the ends of the twine and as will maintain the loops securely in assembled position.

8. A method for sealing receptacles which consists in placing a skirted hood cap upon the mouth portion of a receptacle, placing loops of twine treated with a gummy material upon and around the skirt portion of the cap, and over the end portions of the twine, and exerting a pulling force upon the ends of the twine to cause the loops to contract upon and around the skirt of the cap and upon said end portions of the twine and thus to contract and co-incidentally secure the skirt of the cap upon and around the mouth portion of the receptacle.

9. A method for sealing receptacles which consists in placing a skirted hood cap upon the mouth portion of a receptacle, placing in the form of a clove hitch loops of twine treated with a gummy material upon and around the skirt portion of the cap, and exerting a pulling force upon the ends of the twine to cause the loops to contract upon and around the skirt of the cap and thus to contract and co-incidentally secure the skirt of the cap upon and around the mouth portion of the receptacle.

10. In combination with a bottle, a hooded cap of flexible material covering the mouth of the bottle and having a contractile skirt surrounding the neck of the bottle, and means for contracting and holding contracted the skirt on the neck of the bottle, said means comprising loops of twine encircling the skirt of the cap, and said loops being gummed substantially throughout their circumferential length and, adjacent the end portions of the twine, being intertwined with said end portions in such manner as to permit the loops to be contracted concentrically when said end portions are pulled in opposite directions and as to maintain the loops securely on the skirt of the cap. 15

11. In combination with a bottle, a hooded cap of flexible material for the mouth of the bottle, said cap having a contractile skirt surrounding the neck of the bottle, and means for contracting and holding contracted the skirt on the neck 20 of the bottle, said means comprising at least two loops of twine encircling the skirt of the cap, said loops being gummed substantially throughout their circumferential length and being continuous of each other, and the end portions of the twine being intertwined in the loops, all whereby the loops contract and bind on the skirt when the end portions of the twine are pulled and co-incidentally said end portions are bound and hold the loops in contracted position. 25

12. A binding device for contracting and holding contracted the skirt of a hooded cap on the neck of a bottle, said device comprising at least two loops of twine for encircling the skirt of 35 the cap, said loops being gummed substantially throughout their circumferential length and being continuous of each other, and the end portions of the twine being intertwined in the loops, all whereby the loops constrict and bind on the 40 skirt when the end portions of the twine are pulled and the end portions of the twine are held from retrograde slipping and hold the loops in contracted position. 45

13. A binding device for contracting and holding contracted the skirt of a hooded cap on the neck of a bottle, said device comprising loops of twine for encircling the skirt of the cap and end portions of twine extending from the loops, the end portions of the twine being intertwined 50 with the loops, and said loops and end portions being gummed at the points where they are intertwined, all whereby the end portions are held from retrograde slipping and the loops are held in contracted position after being assembled and 55 secured tightly upon the skirt of the cap.

JOSEPH H. RAMSEY.
